Official Action dated Sep. 5, 2016 from Japanese Design Application No. 2016-004739, with English translation. thereof.

(Continued)

Primary Examiner — Paula Greene(74) *Attorney, Agent, or Firm* — Plumsea Law Group, LLC(57) **CLAIM**

The ornamental design for a loudspeaker, as shown and described.

DESCRIPTION

FIG. 1 is a perspective view of a loudspeaker showing my new design;

FIG. 2 is a front perspective view thereof;

FIG. 3 is a rear perspective view thereof;

FIG. 4 is a front elevational view thereof;

FIG. 5 is a top plan view thereof; and,

FIG. 6 is a side elevational view thereof, the opposite side elevational view being a mirror image thereof.

The broken lines depict environment and form no part of the claimed design.

1 Claim, 3 Drawing Sheets(56)
